UNITED STATES PATENT OFFICE.

KATE STEUERWALD, OF NEW YORK, N. Y.

DESIGN FOR A BELT-BODY.

SPECIFICATION forming part of Design No. 33,017, dated July 31, 1900.

Application filed June 16, 1900. Serial No. 20,601. Term of patent 3½ years.

To all whom it may concern:

Be it known that I, KATE STEUERWALD, a citizen of the United States, residing in the city, county, and State of New York, have invented and produced a new and original Design for a Belt-Body, of which the following is a specification, reference being had to the accompanying drawings, forming part thereof.

Figure 1 is an exterior elevation of my belt-body extended; Fig. 2, a transverse section thereof upon plane of line 2 2, Fig. 1.

As shown in the drawings, the distinguishing feature of my design consists in the series of longitudinal strips *a a*, held apart centrally and at the ends by the cross-bars *b b' b'*, and gathered at *c c*, between said cross-bars *b b' b'*,

the longitudinal strips *a a* thus alternately converging and diverging to form with the cross-bars an open-work design through which the dress of the wearer is exposed more or less, producing an artistic effect or contrast of color.

Having described my invention, what I claim as new, and desire to secure by Letters Patent, is—

The design for a belt-body, as herein shown and described.

KATE STEUERWALD.
